UNITED STATES PATENT OFFICE

RALPH RAGAN, OF ATLANTA, GEORGIA

FAN REGULATING DEVICE

Application filed December 15, 1924. Serial No. 755,974.

This invention is an improvement in chain-tightening and fan regulating devices for internal combustion engines, and one of the principal objects thereof is to provide in a single device, means for readily and accurately tightening the timing chain, and means for automatically releasing the fan at predetermined engine speeds.

It is known to automobile engineers that the power required to drive the cooling fan of an internal combustion engine amounts to considerable, and that above certain speeds of an automobile, this power represents wasted energy, since the rush of air at and above these speeds, due to the travel of the machine, is sufficient to adequately cool the radiator without the use of the fan. One of the objects of my invention therefore, is to conserve the power thus otherwise wasted, by automatically releasing the fan at a predetermined engine speed.

With these and other objects in view which will become more apparent as the description proceeds, the invention resides in the construction, combination and arrangement of parts hereinafter more fully described and claimed, and illustrated in the accompanying drawings in which,

Figure 1 represents a vertical sectional view taken through the timing chain casing of an automobile engine, and showing the invention in place.

Figure 2 represents a transverse sectional view on the line 2—2 of Figure 1, looking in the direction indicated by the arrows.

Figure 3 is a front elevational view of a portion of the chain casing, showing the forward face of the support for the fan and tightener shaft.

Figure 4 is a transverse sectional view on the line 4—4 of Figure 1, looking in the direction indicated by the arrows, and

Figure 5 is a detailed sectional view on the line 5—5 of Figure 3, looking in the direction indicated by the arrows.

Referring more particularly to the drawings, the casing or housing in which the timing chain runs is indicated at 5, and the timing chain is indicated at 6. This chain, as is well known, drives the cam shaft of the engine

(not shown) from the crank shaft (not shown). The chain runs over an idle gear 7, keyed or otherwise secured to the shaft 8, and this shaft is supported in a pair of spaced plates 9 connected together by a bar 10, so as to be integral with each other, the shaft being capable of rotating within the plates 9, through the medium of bearings, preferably ball bearings, as indicated at 11. One of the plates 9 is received in an opening in the rear wall of the chain housing, and the other in a similar opening in the forward wall of the chain housing, the plates being spaced sufficiently apart to coincide with the spacing of the housing walls, and being rotatable as a unit within said housing. Between the plates, the gear 7 is mounted on the shaft 8.

A plate 12 covers the rearmost plate 9, and a plate 13 covers the forward plate 9, these cover plates being respectively secured to the plates through the medium of screws or other fastening means 14. The plates 12 and 13 are of slightly greater diameter than the plates 9, and overhang the housing 5 at the rear and front thereof, so as to confine the plates 9 to rotary movement relative to the casing, and to prevent end play of the plates. The plates 9, together with the bar 10, which connects them, and the cover plates 12 and 13, thus form a unit, which is rotatable relative to the chain housing, the latter being thickened if desired, to form broader bearing surfaces as at 15, for receiving the plates 9. This unit rotatably supports the shaft 8. The bearings will be oiled by the oil thrown from the chain, and a packing gland or similar device indicated generally at 4, may be utilized to prevent loss of oil around the shaft 8.

It is to be noted that the shaft 8 is mounted eccentrically with respect to the plates 9, so that when the plates are rotated in one direction or another, the gear 7 will be moved bodily through the arc of a circle. Hence, upon rotation of the unit supporting the shaft in one direction, the gear will be moved in a direction to tighten the chain, and upon rotation of the support in an opposite direction, the gear will be bodily moved in a direction to loosen the chain.

Means is provided for locking the shaft 100

support in any adjusted position, and this means includes clips 16, mounted on the forward face of the chain housing, such clips at their inner ends over-lying the cover plate 13, and each having a pin 17 engaging in one of a circular series of recesses 18 provided in the cover plate 13, the opposite ends of the clips over-lying the adjacent portions of the housing, and each having a pin 19 engaging in a recess in the housing. The clips are held in place by studs or equivalent means 20, which pass through the clips and are screwed into the housing, and which, when in place, retain the clips in the position indicated in Figure 1, and thus hold the shaft support against rotation.

The clips 16 may, if desired, be arranged in diagonally opposed relation with respect to the shaft support, and if desired, additional clips 30 may be utilized for engaging the outer surface of the plate 13 at the sides which are unengaged by the clips 16, such clips 30, as indicated in Figure 5, being inturned at their inner ends to bear against the cover plate 13, and at their outer ends as at 31, to bear against the housing, studs 32 being utilized to tighten the clips against the housing and the cover plate.

When it is desired to tighten the chain, the studs 32 are loosened to relieve the pressure on the clips 30, the studs 20 are loosened sufficiently to allow the clips 16 being withdrawn to disengage the pins 17 with the recesses 18, whereupon the shaft support may be bodily rotated to secure the desired adjustment of the chain. The clips 16 may be then reengaged with the cover plate, the pins entering the new recesses turned into registration with them through the adjustment, and the studs 20 and 32 tightened down to secure the clips in place.

Upon the reduced outer end of the shaft 8, is keyed or otherwise secured the hub 21 of the fan assembly, such hub including a cylindrical portion 22 which rotatably receives the cylindrical portion 24 of the hub of the fan 23, as shown in Figure 1. A taper faced ring 25 is slidably carried inside the hub cylinder 22. Against the tapered face of the ring weights 26 bear. These weights are carried at the ends of a curved spring 27 which surrounds the central portion of the fan assembly hub 21, and are fixed thereto as by pins 29 in concentric relation with the shaft 8. A nut 28, threaded on the outer end of the shaft 8 and bearing against the hub of the fan, serves as a means whereby the fan hub may be adjusted relatively to the hub 21, and whereby, as will be readily understood, when the nut 28 is turned up, the taper faced ring 25 may be tightened against the weights 26. Similarly, if it is desired to reduce the frictional engagement of the ring, with the weights on one side, and the fan

hub on the other, the nut 28 may be backed to the desired degree.

From the foregoing description of the fan assembly, it will be observed that the fan, through the frictional contact of the weights, the ring, and the fan hub, will be driven by the engine, until the latter has reached such speed that the centrifugal action will release the pressure of the weights 26 against the ring to such an extent that the inertia of the fan will overcome the frictional engagement between the fan hub and the ring, or the weights and the ring, whereupon the fan will be released and will cease revolving while the engine is turning over at and above the predetermined speed. Thus the engine may be relieved of the load of the fan at any desired predetermined speed. By tightening the nut 28, or loosening it, to the desired degree, the engine speed at which the fan will be released may be varied.

The foregoing detailed description has been given for purposes of illustration only, and no undue limitations should be deduced therefrom, but the appended claims should be construed as broadly as permissible, in view of the prior art.

Having thus described my invention what I claim as new and desire to secure by Letters Patent is:—

1. In an internal combustion engine, the combination with a fan having a hollow hub, and means for driving the fan from the engine, of means mounted within the hub of the fan for releasing the fan from said driving means at predetermined engine speeds.

2. In an internal combustion engine, the combination of a fan, means within the hub of the fan for driving the fan, and for releasing the fan from its driving means at predetermined engine speeds, and adjusting means without the hub of the fan whereby the predetermined speed may be varied.

3. In a fan regulating device for internal combustion engines, the combination of a shaft, means for driving the same, a fan assembly hub rotatable with the shaft, a fan including a hub rotatable with respect to the fan assembly hub, a centrifugally controlled spring pressed weight rotatable with the fan assembly hub and carried therein, friction transfer means between the weight and the fan hub, and means for adjusting the fan hub relative to the weight.

In testimony whereof I hereunto affix my signature.

RALPH RAGAN.
